US00D445404S

(12) **United States Design Patent** (10) Patent No.: **US D445,404 S**
Decosse (45) Date of Patent: ** Jul. 24, 2001

(54) **APPARATUS FOR SWITCHING ELECTRIC POWER**

(75) Inventor: **Jean Decosse**, Chirens (FR)

(73) Assignee: **Schneider Electric Industries SA**,
Rueil-Malmaison (FR)

(**) Term: **14 Years**

(21) Appl. No.: **29/127,758**

(22) Filed: **Aug. 14, 2000**

(30) **Foreign Application Priority Data**

Feb. 14, 2000 (FR) 00 1050

(51) LOC (7) Cl. **13-03**

(52) U.S. Cl. **D13/159**

(58) Field of Search D13/159, 160;
200/237, 293, 297

(57) **CLAIM**

The ornamental design for an apparatus for switching electric power, as shown and described.

DESCRIPTION

FIG. 1 is a front elevational view of an apparatus for switching electric power showing my design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The colors and indicia shown in the Figures are hereby disclaimed and form no part of the claimed invention.
